UNITED STATES PATENT OFFICE.

JULIUS KAHN, OF DETROIT, MICHIGAN, ASSIGNOR TO TRUSSED CONCRETE STEEL COMPANY, OF DETROIT, MICHIGAN, A CORPORATION OF MICHIGAN.

EXPANDED-METAL TENSION MEMBER.

No. 799,653.

Specification of Letters Patent.

Patented Sept. 19, 1905.

Application filed March 24, 1905. Serial No. 251,752.

To all whom it may concern:

Be it known that I, JULIUS KAHN, a citizen of the United States, and a resident of Detroit, in the county of Wayne and State of Michigan, have invented a new and useful Expanded-Metal Tension Member for Combined Concrete and Metal Construction, of which the following is a specification.

My invention relates to means for resisting the tensional stresses that develop in composite construction and also to means for assisting the concrete of such construction to overcome the compression stresses.

The objects of my improvements are to provide a cheap and powerful tension member for combined concrete and metal construction that shall be so formed that the tensional stresses set up in the lower portions of such construction shall be entirely taken up by such tension member, that such stresses that are set up some distance above the lower tension member shall be provided for, that such upper and lower tension members shall be integrally connected by ties that shall assist in the union between the concrete and metal, and to provide means for preventing the individual tension members from being displaced relative to each other. I attain these objects by the construction illustrated in the accompanying drawings, in which—

Figure 1 is an end view, and Fig. 2 a plan, of one of my rolled bars previous to being expanded. Fig. 3 is an end view, and Fig. 4 is a plan, of another form of bar previous to being expanded. Fig. 5 is a view of the bar of Figs. 1 and 2 expanded and partially enclosed in concrete. Figs. 6 and 7 are side views of two forms of my expanded metal. Fig. 8 is an end view of another form of my improved tension member. Fig. 9 is a cross-sectional view of the tension member on the line 9 9 of Fig. 7. Fig. 10 is an end view of a tension member for heavy composite beams, and Fig. 11 is a side view of the same. Similar reference characters refer to like parts throughout the several views.

The tension members shown in the drawings are formed by first rolling out a bar to form parallel tension-rods connected by webs. In Figs. 1, 2, 5, 6, 7, and 9 these rods A are round, while in the other figures the rods B are square. Any other desirable cross-section may be used, however. The webs C be-

tween the rods are next sheared, preferably by passing the bars through rotary shears, in the manner shown in Figs. 2 and 4. Cross-cuts D are joined at their opposite ends to the longitudinal cuts E, extending in opposite directions. This leaves tie members F connected at their opposite ends to the adjacent rods. The rods are next separated, so that each alternate rod will be in a different plane from that next adjacent, as shown in Figs. 5, 8, 9, and 10. The tie members extend across the space between the rods, the portions of the webs that are still united to the rods forming projections G, to which the tie members are attached. If the rods are separated as far as possible, the tie members will extend at right angles to the rods, as in Figs. 5 and 6. If the lower rods in Fig. 5 were moved endwise in opposite directions, the tie members on opposite sides of the upper rod would be inclined in opposite directions, as shown in Fig. 7. When concrete is moulded around the tension members, as indicated by dotted lines in Figs. 6 and 7, composite trusses are formed, the concrete in each case together with the upper rod acting as the compression members of the truss. In Fig. 6 the action is that usually found in the Howe truss, while in Fig. 7 the Pratt truss is exemplified. When the form shown in Fig. 7 is used, there is a possibility that the lower rods will slide endwise in opposite directions under the weight of the superimposed moist concrete. To prevent this, the lower rods are locked in place by means of the clamp H. The upper and lower rods may be formed of the same size or their sizes may differ, as shown in Fig. 8, where the lighter upper rods K together equal the size of the lower rod L. This construction is often desirable when the load is variable and unevenly distributed. For heavy structures a series of sets of rods in parallel planes are desirable. These are rigidly held in place by the cross-clamps M and N, which prevent them from spreading. Such a structure requires very little false work—in fact, when well constructed forms a powerful truss. It will be noticed that in all these constructions all the rods are of comparatively large size to withstand the tensional stresses, while the tie members are light, no great stress coming on them, their duty being merely to hold the rods in position.

tion while the composite beam is being molded and to prevent the rods slipping in the concrete under stress. They also serve to transmit tensional stresses set up in the concrete 5 to the tension members, and so serve as do the diagonal or vertical tension members of Pratt and Howe trusses.

Having now explained my invention, what I claim as new, and desire to secure by Letters 10 Patent, is—

1. In an expanded-metal construction, the combination of a series of metal rods in one plane, a second series of parallel rods in a second plane parallel to the first, connecting tie 15 members extending from a rod in one plane to two adjacent rods in the other plane, all said rods and tie members being integral with each other, and cross-connecting members engaging the rods in one of the planes to hold 20 them in position.

2. In an expanded-metal construction, the combination of a rod in one plane, a series of rods in a second plane parallel to the first, connecting tie members extending from the 25 first rod to two adjacent rods in the plane below, all said rods and tie members being integral with each other, and a cross-connection engaging the rods in said second plane to hold them in position.

3. An expanded-metal construction, comprising a series of metal rods in one plane, a second series of parallel rods in a second plane parallel to the first, connecting tie members

extending from a rod in one plane to two adjacent rods in the other plane, all said rods and 35 tie members being integral with each other, the tie members being of less width and thickness than the rods.

4. An expanded-metal construction comprising a rod in one plane, a plurality of rods 40 in a different plane parallel to the first, and a series of tie members of less width and thickness than said rods to position the same, all the members being integral with each other.

5. An expanded-metal construction, comprising a rod having a series of projections on each side of the same, a pair of parallel rods lying in the same plane and having a series of reduced projections extending from their adjacent sides, and a series of tie members 50 connecting the projections of the first rod with those of the other two, all said rods and tie members being integral with each other.

6. An expanded-metal construction comprising a rod in one plane, a plurality of rods 55 in a different plane, and a series of tie members to position the rods, all the members being integral with each other.

In testimony whereof I have hereunto set my hand in the presence of two subscribing 60 witnesses.

JULIUS KAHN.
